2 Claims. (Cl. 260—564)

ABSTRACT OF THE DISCLOSURE

The guanidine derivatives of the present invention are those which are encompassed by the following formula:

wherein R represents a cycloalkyl group of from 5 to 7 carbon atoms; R_1 and R_2 each represent an alkyl of from 1 to 4 carbon atoms and R_3 , R_4 and R_5 each represent a hydrogen atom or an alkyl of from 1 to 4 carbon atoms. The invention also includes the hydrate forms and the physiologically acceptable acid addition salt forms of the respective compounds since it has been discovered that these forms also exhibit hypotensive activity.

Applicant has found that certain guanidine compounds, which are described in detail below, possess particularly valuable hypotensive activity, especially against renal and neurogenic hypertension. In addition they possess a duration of action which is particularly convenient in practice, the duration of action being neither impractically short nor undesirably long. Furthermore, the onset of action is quick enough to obtain a substantially immediate effect due to a direct action on the peripheral arteries. The compounds can be safely administered by injection as well as orally in contrast to a number of previously proposed guanidine hypotensives. The compounds also have the important practical advantage that they can be prepared from readily available starting products, as is also described below.

According to the present invention we provide compounds of the general formula

and their hydrates and physiologically acceptable acid addition salts, where R is a cycloalkyl group containing 5-7 carbon atoms in the ring and which may be substituted with one or more alkyl groups having 1-4

R^1 is a hydrogen atom or an alkyl group having 1-4 carbon atoms.

R^2 is an alkyl group having 1-4 carbon atoms.

R^3 , R^4 and R^5 , which may be the same or different, are hydrogen atoms or alkyl groups having 1-4 carbon atoms.

The substituents R^1 and R^2 may be straight or branched chain alkyl groups i.e. methyl, ethyl, propyl, isopropyl, butyl, isobutyl or *t*-butyl groups. The preferred compounds are those in which R^2 is methyl and R^1 is hydrogen or methyl.

The substituents R^3 , R^4 and R^5 are preferably all hydrogen.

The compounds in which R^1 and R^2 are both alkyl groups, especially both methyl groups, are of especial interest in that they have been found to produce a particularly marked action on the peripheral blood vessels and the compound in which R^1 and R^2 are both methyl, R is cyclohexyl and R^3 , R^4 and R^5 are hydrogen is especially noteworthy in this respect. The compounds in which R^2 is hydrogen are especially useful for oral administration; the compound 2 - (cyclohexylamino)-propyl-guanidine is particularly important in that it gives a uniform response by this route as well as by injection, in contrast to some previously proposed guanidine hypotensives and is substantially equally effective by either route.

Where R^3 , R^4 and/or R^5 is an alkyl group this may, be a straight chained or branched chained alkyl group, e.g. a methyl, ethyl, butyl group etc.

20 Where the groups R^1 and R^2 are different, the compounds exist as optical isomers and racemic mixtures and these isomers and their racemates constitute features of the present invention. Thus, for example, 2 - (cyclohexyl-amino)-propyl guanidine exists as *d* and *l*-isomers and as 25 a racemic *d,l*-mixture.

The group R is preferably a cyclohexyl group. The bases according to the invention is:

30 cases according to the invention in general have two basic groups and so form both mono- and di- acid addition salts. Such salts include, for example, salts with mineral acids, e.g., hydrochlorides, hydrobromides, sulphates, perchlorates, nitrates, phosphates etc. and salts with organic acids, e.g. formates, acetates, propionates, glycolates, lactates, pyruvates, malonates, succinates, maleates, fumarates, malates, tartrates, citrates, oxalates, benzoates, salicylates, methanesulphonates, ethanesulphonates, p-toluene sulphonates etc.

The new guanidines according to the invention may be used in medicine in the form of pharmaceutical compositions containing one or more of the new compounds in conjunction with one or more pharmaceutical carriers or excipients suitable for oral, rectal or parenteral administration or inhalation therapy. The compositions are preferably in dosages unit form to facilitate prescription, for example in the form of tablets, pills, chewing gum, sachets, capsules, suppositories, ampoules etc. and each dosage unit preferably contains 1 to 400 mg. of the active guanidine compounds, advantageously 5 to 100 mg., for example 10 to 50 mg.

The carrier in the solid oral forms may, for example, include gelatin, lactose, starch, talc, magnesium stearate, hydrogenated oils, polyglycols etc. Suppositories may contain a conventional suppository base e.g. cocoa butter, polyglycols etc. with or without surface active agents. The injectable preparation

The injectable preparations may take the form of aqueous or oily solutions or suspensions. Suitable vehicles for injectable preparations include for example, sterile pyrogen-free water, parenterally acceptable oils or other non-aqueous media or oil-containing emulsions, if desired containing suspending, dispersing, stabilising, emulsifying, solubilising or buffering agents.

The compositions may also take the form of liquid oral preparations such as syrups, elixirs, emulsions etc. Which may contain suspending, emulsifying, stabilising or thickening agents together with acceptable sweetening, flavouring, colouring or preserving agents.

Preparations for inhalation preferably take the form of aerosols containing, for example, conventional aerosol propellants.

The compounds according to the invention may be prepared in any convenient way. According to a further embodiment, the compositions include powders or granules for reconstitution immediately before injection.

3

ture of the invention, there is provided a process for the preparation of compounds of the general formula

(where R is a cycloalkyl group containing 5-7 carbon atoms in the ring which may be substituted; R¹ is a hydrogen atom or an alkyl group having 1-4 carbon atoms; R² is an alkyl group having 1-4 carbon atoms; and R³, R⁴ and R⁵, which may be the same or different, are hydrogen atoms or aliphatic groups having 1-4 carbon atoms) in which an amine of the general formula

(where R, R¹ and R² have the above meanings and R⁶ is a hydrogen atom or a group

is reacted, where R⁶ is hydrogen, with a thiourea derivative of the general formula

(where R⁷ is an alkyl or aralkyl group, R⁵ is a hydrogen atom or an alkyl group having 1-4 carbon atoms and R³ and R⁴ have the above meanings) or a salt thereof, with nitrosoguanidine, with N-nitrosoguanidine with an N-alkyl-N-cyanamide, with N-nitrosoguanidine or with a cyanogen halide followed by nitrosoguanidine or with a cyanogen halide-reaction product with ammonia or an amine, or is reacted, where R⁶ is a group

with mercuric oxide and ammonia or an amine.

The salt of the thiourea derivative may, for example, be a mineral acid salt such as a hydrohalide, nitrate or sulphate. The reaction with the thiourea derivative may be effected in the presence or absence of a solvent, suitable solvents, where present, including water and water-miscible organic solvents such as water miscible alcohols, ethers, ketones, or carboxylic acids, e.g. methanol, ethanol, propanol, dioxan, tetrahydrofuran, acetone, methyl ethyl ketone, acetic acid etc. The reaction temperature is not especially critical and normal temperature is generally convenient, although higher temperatures, e.g. up to the boiling point of the medium, can also be used.

According to a modification of the process of the invention the compounds of Formula I as defined above can be prepared by reacting the compound of Formula II wherein R⁶ is hydrogen with a compound of the general formula

(in which R⁸ is an alkoxy or aralkoxy group or a group of the formula

and R³, R⁴ and R⁵ have the above meanings) or a salt thereof.

5

The reaction of the amine II with cyanamide gives

compounds having an unsubstituted guanidine group; the

reaction of the amine II with an unsubstituted N-nitroso

guanidine gives an unsubstituted guanidine group but the

nitrosoguanidine may carry an N-alkyl substituent to yield

an N-alkyl guanidine.

The amines of general Formula II used in the above methods can be conveniently prepared by reduction of the corresponding nitriles of the general formula

The above nitriles can be prepared, for example, by condensation of an amine RNH₂ with an aldehyde or ketone R¹-CO-R² followed by treatment with a cyanide. The aldehyde or ketone is preferably in the form of its bisulphite adduct, e.g. sodium acetaldehyde bisulphite, sodium acetone bisulphite etc. The cycloalkyl amine is advantageously added dropwise to a solution of the bisulphite adduct in an aqueous solvent such as water. The cyanide is preferably an alkali metal cyanide, e.g. sodium, potassium cyanide etc.

Alternatively the amine RNH₂ may be condensed with a cyanhydrin of the aldehyde in ketone R¹-CO-R² to give the nitrile directly.

The reduction of the nitrile is preferably effected with a metal hydride reducing agent, e.g. lithium aluminium hydride in a solvent medium e.g. ether or tetrahydrofuran.

The amines of Formula II above may also be prepared by condensation of a cycloalkanone with a diamine

followed by reduction of the resulting Schiff's base.

Where the preparative method leads to an unsubstituted guanidine group, the substituents R³, R⁴ and R⁵ may be introduced subsequently, by alkylation, for example using conventional techniques such as reaction with an alkyl halide, sulphate or aromatic-sulphonate alkylating agent.

The methods of preparation of the new compounds described herein will in general give rise to the compounds in the form of salts. The free base may be prepared from the salt by treatment with a strong anion exchange resin or treatment with caustic alkali or silver oxide. Other salts may be formed from the free base so obtained. Alternatively if it is desired to change the anion of an acid addition salt, conventional ion exchange techniques may be used, e.g. using anion exchange resin.

In order that the invention may be well understood we give the following examples by way of illustration only (all temperatures are in ° C.):

55

EXAMPLE 1

To a solution of 15.4 grams of S-methyl-isothiourea sulphate in 50 millilitres of water was added 15.6 grams of 2-(cyclohexylamino)propylamine. After standing the mixture overnight at room temperature, during which time methyl mercaptan was evolved, the reaction was completed by heating on a boiling water bath for one hour. After cooling, the solution deposited crystals, which after collecting and drying, weighed 22.6 grams and had M.P. 198°. These were recrystallised from water. There was thus obtained 2-(cyclohexylamino)propyl-guanidine sulphate of M.P. 206° (corr.).

The 2-(cyclohexylamino)propylamine used in the above preparation, was made as follows: Sodium acetaldehyde bisulphite (364 grams) was dissolved in water (800 millilitres) and to the solution, cyclohexylamine (198 grams) was added dropwise at room temperature during the course of thirty minutes, with mechanical stirring. The mixture was allowed to stand for a further one hour

75 after which it was treated with a solution of sodium

cyanide (108 grams) in water (200 millilitres). On standing in a separating funnel the reaction mixture formed two layers. The upper layer of nitrile was collected. The lower layer was extracted with two 500 millilitre portions of ether, and the ether extracts were added to the upper layer of nitrile. The total ether solution so obtained was dried by standing over anhydrous sodium sulphate. After distilling off the ether the residual oil was fractionated by distillation under reduced pressure and furnished 240 grams of 2-(cyclohexylamino) propionitrile of B.P. 106° C./mm., n_{D}^{20} 1.4688. A solution of 176 grams of 2-(cyclohexylamino) propionitrile in 300 millilitres of dry ether was added to a suspension of 58 grams of lithium aluminium hydride in 200 millilitres of dry ether during one hour. The mixture was then refluxed for 3 hours and allowed to cool. With care, 50 millilitres of water were slowly added, followed by 60 millilitres of 20% sodium hydroxide solution and finally another 140 millilitres of water. After filtration the ethereal solution was dried over anhydrous sodium sulphate. The ether was removed by evaporation and the product 2-(cyclohexylamino) propylamine distilled at reduced pressure. It has B.P. 105-7°/18 mm., and n_{D}^{20} 1.4742. Yield 122 grams.

EXAMPLE 2

A mixture of S-methylisothiourea sulphate (15.8 grams), 2-cyclohexylamino-2-methyl-propylamine (16.6 grams) and water (50 millilitres) was allowed to stand overnight at room temperature. The evolution of methyl mercaptan was completed by heating the solution on a water bath for another hour. After cooling, the crystals of 2-cyclohexylamino-2-methyl-propylguanidine sulphate which had separated, were recrystallised from a mixture of alcohol and water and had M.P. 203-6° C. Yield 18 grams.

The 2-cyclohexylamino-2-methyl-propylamine required was prepared in the following way: A solution of 120 grams of acetone sodium bisulphite in 400 millilitres of water was slowly treated with 66 grams of cyclohexylamine. After standing for one hour the mixture was treated with 36 grams of sodium cyanide dissolved in 70 millilitres of water. The upper layer of 2-cyclohexylamino-2-methyl-propionitrile which formed was removed, and the lower layer extracted three times with ether. The ether extracts were combined and added to the original upper layer of nitrile. The other solution so obtained was dried over anhydrous sodium sulphate. The residue, after removal of the ether, was distilled at reduced pressure to yield 47 grams of the pure nitrile, which solidified on standing, and had M.P. 52° C. A solution of the 2-cyclohexylamino-2-methyl-propionitrile (44 grams) in dry ether (75 millilitres) was gradually added to a suspension of lithium aluminium hydride (13 grams) in 600 millilitres of ether. The reaction mixture was refluxed, with mechanical stirring, for 3 hours and then left to stand overnight. Water (10 millilitres) was carefully added, followed by 20% sodium hydroxide (13 millilitres) and finally water (30 millilitres). After cooling the filtered solution was dried over sodium sulphate. The ether was removed by evaporation and the residual oil fractionated to yield 24 grams of 2-cyclohexylamino-2-methyl-propylamine of B.P. 112-114° C./18 mm., n_{D}^{20} 1.4721.

EXAMPLE 3

A solution of sodium propionaldehyde bisulphite was prepared by careful addition, with ice cooling, of propionaldehyde (58 grams) to aqueous sodium bisulphite (300 millilitres of 37%). To the solution, cyclohexylamine (99 grams) was added dropwise during the course of 30 minutes at room temperature under mechanical stirring which was continued for a further 60 minutes. A solution of sodium cyanide (100 grams) in water (200 millilitres) was then added and the resultant mixture was stirred for a further 3 hours and then allowed to stand overnight. The so formed 2-cyclohexylamino-n-butyronitrile was extracted with ether and the ether ex-

tract dried over anhydrous sodium sulphate. After removal of the ether, the nitrile was purified by distillation and had B.P. 106-108°/12 mm., n_{D}^{18} 1.437. A solution of the so obtained 2-cyclohexyl-n-butyronitrile (35.2 grams) in dry ether (100 millilitres) was slowly added to a suspension of lithium aluminium hydride (10 grams) in dry ether (500 millilitres) and the mixture refluxed for 3 hours. After cooling it was treated carefully with water (8 millilitres) followed by 25% caustic soda solution (10 millilitres) and finally water (24 millilitres). The ethereal solution after filtration was dried over anhydrous sodium sulphate. Following removal of the ether, the 2-cyclohexylamino-n-butyramine was distilled and had B.P. 110°/15 mm., n_{D}^{20} 1.476. Yield 22.3 grams. 10 A mixture of 2 - cyclohexylamino - n - butylamine (17 grams), S-methylisothiourea sulphate (15.4 grams), and water (50 millilitres) was heated on a boiling water bath for 2 hours. During this time methyl mercaptan was evolved and a solid deposited. After cooling the solid product, 2 - cyclohexylamino-n-butylguanidine sulphate, was collected on a filter and after recrystallisation from 150 millilitres of 33% aqueous alcohol had M.P. 125° C. Yield 19.7 grams.

EXAMPLE 4

25 2-cyclohexylaminopropylamine (7.8 grams), S-ethyl-N-methylisothiouronium sulphate (11 grams) and alcohol (5 millilitres) were mixed and heated on a water bath for one hour during which ethyl mercaptan was evolved. The resulting oily residue was stirred with ethyl acetate, and after separation, was dissolved in 200 millilitres of water. The aqueous solution was passed down a chromatographic column of De-Acidite FF (OH form) and the emergent liquor concentrated under reduced pressure to small volume. It was then neutralised with 30 5 N-sulphuric acid and treated with acetone. The gummy solid which formed was removed and hardened by trituration with fresh acetone. In this way was obtained as a white solid, 1 - (2-cyclohexylaminopropyl) - 3 - methylguanidine sulphate, M.P. 236° (decomp).

EXAMPLE 5—ORAL ELIXIR

Formula

Active ingredient	-----	mg	200
Alcohol 60 over/proof (91.4% v/v.)	-----	ml	10
Sucrose B.P.	-----	g	30
Methyl hydroxybenzoate B.P.	-----	mg	150
Propyl hydroxybenzoate B.P.	-----	mg	100
Flavouring and colouring agents	-----	q.s.	
50 Water to 100 ml.			

Method of preparation

The sucrose was dissolved in 50 ml. water, the active ingredient added and dissolved. To this solution was added a solution of the methyl hydroxybenzoate and the propyl hydroxybenzoate in alcohol into which the flavouring agents had been mixed. A solution of the colouring agents was then added and the volume made up to 100 ml. before mixing well and filtering through a No. 3 sintered glass filter.

5 ml. (one teaspoonful) of the elixir contains 10 mg. of the active ingredient.

The active ingredient in this composition is 2-(cyclohexylamino)propylguanidine sulphate or 2-(cyclohexylamino)-2-methyl propylguanidine sulphate.

EXAMPLE 6—INJECTION (10 MG./ML.)

Formula

Active ingredient	-----	g	1.0
70 Water for injection B.P. to 100 ml.			

Method of preparation

The active ingredient was dissolved in sufficient water for injection to make 100 ml. The solution was sterilised by filtration through a 5/3 sintered glass filter or sterilis-

7
ing grade membrane filter and aseptically packed in sterile 1 ml. ampoules.

EXAMPLE 7—INJECTION (25 MG./ML.)

Formula	5
Active ingredient	g 2.5
Sulphuric acid, dilute B.P.C.	ml 4.0
Sodium hydroxide solution B.P. (Appendix I) q.s.	
pH	7.4
Water for injection B.P. to 100 ml.	

Method of preparation

The active ingredient was dissolved in the sulphuric acid which had previously been made up to 70 ml. with water for injection. After adjusting the pH to 7.4 with the sodium hydroxide, the solution was made up to 100 ml. with water for injection and sterilised by filtration through a 5/3 sintered glass filter or a sterilising grade membrane filter before being aseptically packed in sterile 1 ml. ampoules.

The active ingredient in this composition is 2-(cyclohexylamino)propylguanidine sulphate, or 2-(cyclohexylamino)-2-methyl propylguanidine sulphate.

EXAMPLE 8—TABLET

Formula	15
Active ingredient 60 mesh (B.S.) powder	mg 25.0
Lactose, B.P.	mg 87.5
Starch, B.P. maize	mg 37.5
10% w./v. maize starch paste	q.s. 30
Magnesium stearate	percent w./w. 1.0

Method of preparation

The active ingredient, lactose and starch were damped with starch paste and mixed thoroughly. The wet granules

were passed through a 12 mesh (B.S.) screen and dried at 50° C. The dried granules were passed through an 18 mesh (B.S.) screen, blended with the magnesium stearate and compressed into tablets.

5 Compression weight: 0.155 g.; Punches: $1\frac{1}{3}$ inch standard concave; machine: Manesty F.3.

The active ingredient in this composition is 2-(cyclohexylamino)propylguanidine sulphate, or 2-(cyclohexylamino)-2-methyl propylguanidine sulphate. The disintegration time of the tablets containing A is about 55 sec.; 10 the disintegration time of the tablets containing B is about 50 sec.

EXAMPLE 9—INJECTION (10MG./ML.)

Formula	15
Active ingredient	g 1.0
Sulphuric acid, dilute B.P.C.	ml 2.0
Sodium hydroxide solution B.P. (Appendix I) q.s. 20	7.4
Water for injection to 100 ml.	

Method of preparation, as in Example 7.

I claim:

1. A compound selected from the group consisting of 25 2-(cyclohexylamino)-2-methyl-propyl-guanidine-1, a hydrate thereof and a physiologically acceptable acid addition salt thereof.

2. 2-(cyclohexylamino)-2-methyl-propyl-guanidine-1.
